UNITED STATES PATENT OFFICE.

FRANK E. BESSLER, OF AKRON, OHIO.

ATTACHMENT FOR DRILL PRESSES.

Application filed May 2, 1921. Serial No. 466,064.

To all whom it may concern:

Be it known that I, FRANK E. BESSLER, a citizen of the United States, residing at Akron, in the county of Summit and State 5 of Ohio, have invented a new and useful Attachment for Drill Presses, of which the following is a specification.

This invention aims to provide novel means whereby a drill press may be converted into a tapping machine, the shaft which carries the tapping tool being advanced and retracted automatically, it being necessary, merely, for the operator to feed the work under the tapping tool.

15 The invention aims to improve generally, and to enhance the utility of, devices of that sort hereinafter described.

I do not bind myself to the specific form set forth, since, within the scope of what 20 is claimed, a mechanic may work changes without departing from the spirit of the invention.

In the drawings:—Figure 1 shows in perspective, an attachment constructed in accordance with the invention and applied to a drill press; Figure 2 is a side elevation of the device forming the subject matter of this application; Figure 3 is a longitudinal section through the mechanism which is 25 mounted on the main shaft; Figure 4 is a sectional view illustrating the connection between the main and auxiliary shafts; Figure 5 is an elevation of the mechanism shown in Figure 4; Figure 6 is a cross section on the line 6—6 of Figure 3; Figure 7 is a section on the line 7—7 of Figure 3; Figure 8 is a section on the line 8—8 of Figure 3; Figure 9 is a fragmental side elevation showing one of the cam tracks and attendant parts; Figure 10 is a bottom plan 30 of the cam track.

The numeral 1 denotes the frame of a drill press, the frame carrying bearings 2, 3, and 4. The main shaft 5 of the drill 35 press is journaled in the bearings 2 and 3, the auxiliary or drill-carrying shaft 59 being journaled in the bearing 4.

Assuming that it is desired to transform 40 a drill press into a tapping machine, the cone pulley 6, which usually is fast to the shaft 5, is journaled for rotation thereon and is held against longitudinal movement on the shaft by a screw 11 in the pulley, and a groove 12 in the shaft. The hub of 45 the pulley 6 is supplied with an oil chamber 7 fed through any suitable means 8. A

clutch member 9 is attached by anchor bolts 10 to the inner end portion of the pulley 6. A pulley 14 is journaled on the main shaft 5 and is held against longitudinal movement 50 thereon by a screw 15 in the pulley, and a groove 16 in the shaft. A clutch member 17 is secured at 18 to the pulley 14.

A bracket 19 is attached at 20 to the frame 1 and supports a U-shaped frame 21, 65 attached to the bracket 19, as indicated at 22. The numeral 23 denotes a slide carrying an oil cup 24 for the lubrication of parts which are located beneath the slide. Yokes 25 are secured at 26 to the slide. Clutch 70 members 27 and 31, mounted on the shaft 5, are journaled in the yokes. The slide 23 thus is supported from the shaft 5, and is movable longitudinally of the shaft, the slide being prevented from tilting transversely of the shaft, by engagement with the end portions of the frame 21. The clutch member 27 has a hub 28 splined to the shaft 5 for sliding movement thereon, the spline construction being indicated at 80 29. There is an opening 30 in the clutch member 17, for the reception of the hub 28 of the clutch member 27, the clutch member 27 being adapted to cooperate with the clutch member 17. The hub 32 of the 85 clutch member 31 is splined at 33 to the shaft 5, to the end that the clutch member 31 may be slid into and out of engagement with the clutch member 9. The clutch member 9 has an opening 34 for the reception 90 of the hub 32 of the clutch member 31.

A shift bar 35 is mounted for right line reciprocation in the ends of the frame 21. Levers 36 and 37 are fulcrumed intermediate their ends, as at 38, on the frame 21. The 95 lower ends of the levers 36 and 37 are pivoted to the ends of the shift bar 35. The lever 37 cooperates with the clutch member 31, the lever 36 cooperating with the clutch member 27. Stops 39 are mounted adjustably, as 100 indicated at 40, on the shift bar 35, for movement longitudinally of the shift bar.

A screw 41 is connected at 42 to the shaft 5, to rotate therewith, the screw being located between the ends of the frame 21, and 105 being held thereby against movement longitudinally of the shaft 5. The screw 41 is threaded into a nut 43 having a reduced depending shank 44 which is notched at 45 to receive the shift bar 35, the shank 44 of the 110 nut or traveller 43 being located between the stops 39. Recesses 46 are formed in the

2

sides of the nut 43, actuators 47 being slideable in the recesses, the actuators having oppositely slanting surfaces as shown in Figure 9. The actuators 47 have shanks 48 5 slideable in the nut 43 and connected, below the body of the nut, to a cross head 49 which is slideable on the shank 44 of the nut. Compression springs 50 are located in the recesses 46 and tend to thrust the actuators 10 upwardly. Cam tracks 51 are provided, the same comprising, each, members 52 and 52^a, tongued and grooved together as shown at 53, to the end that the effective length of the cam track may be increased. The members 52 and 52^a of the cam tracks are adjustably secured at 54 to the side portions of the slide 23. The actuators 47 cooperate with the cam tracks 51 in a way which will be pointed out hereinafter.

20 A beveled pinion 55 on the main shaft 5 meshes into a beveled pinion 56 on the auxiliary or drill-carrying shaft 59, the beveled pinions being located beneath a housing 57, supported as indicated at 58. The hub of 25 the beveled pinion 56 is journaled in the bearing 4 and is splined at 60 to the shaft 59, the construction being such that, although the pinion 56 will drive the shaft 59, the shaft 59 can move endwise in the 30 pinion. A screw 62 is secured at 61 to the shaft 59 and is threaded into a support 63 having reduced ends 64 received in guide slots 65 formed in brackets 66 and 67, the bracket 66 being connected at 75 to the bearing 3, and the bracket 67 being connected at 76 to the bearing 4. Springs 68 35 are located in the brackets 66 and 67, and, cooperating with the parts 64 of the support 63, hold the support securely but yieldably in the position shown in Figure 4. Screws 69 are threaded into the brackets 66 and 67 and afford means for adjusting the compressive effort of the springs 68. There 40 is a depression 70 in the upper surface of 45 the support 63. An oil cup 71 is mounted on a bracket 72 secured at 79 to the support 63. The oil proceeding from the cup 71 is discharged by the bracket 72 into the depression 70 of the support 63, and in this 50 way, the screw 62 is lubricated.

When the shaft 5 is rotated in one direction, motion will be transmitted by the beveled pinions 55 and 56, and the spline 60, to the shaft 59. The shaft will be rotated, 55 and will be fed downwardly, because the screw 62 is threaded into the support 63. When the shaft 5 is rotated in an opposite direction, reverse rotation will be transmitted to the shaft 59, the screw 62 effecting a 60 raising of the shaft 59. From the foregoing it will be obvious that a tap on the end of the shaft 59, will be fed downwardly a predetermined distance and be retracted, the tap 65 being rotated at the same time. In case that a destructive or unusual strain is put

on the shaft 59, the springs 68 will yield. Further, the springs 68 enable the shaft 59 to be raised and lowered by the common controlling mechanism 100, provided for that purpose upon a drill press.

70 It has been pointed out hereinbefore that the shaft 5 is rotated first in one direction and then in an opposite direction. Let it be supposed, further, that the pulley 6 is rotated continuously in one direction, the pulley 14 being rotated continuously in an opposite direction. A means is provided whereby the pulleys 6 and 14 are coupled one at a time, automatically, to the shaft 5, to secure a reversal of the shaft, and the 75 operation of this means will now be set forth.

Suppose that the clutch member 31 is coupled to the clutch member 9, the clutch member 27 being out of engagement with the clutch member 17. Then, the shaft is 80 rotated by a train of elements including the pulley 6, the clutch member 9, the clutch member 31, and the spline 33. The screw 41 is rotated, and the nut 43 moves to the right in Figure 3, the shank 44 of the nut 90 engaging the right stop 39 and moving the shift bar 35 to the right, the lever 37 swinging away from the clutch member 31. The lever 36 moves the clutch member 27 into 95 engagement with the clutch member 17 and couples the pulley 14 to the shaft 5, the slide 23 moving to the left and disengaging the clutch member 31 from the clutch member 9. Since the pulleys 14 and 6 rotate in 100 opposite directions, the direction of rotation of the shaft 5 will be reversed by the operation above set forth. There is a short but appreciable interval when the clutch member 31 is out of engagement with the clutch member 9, and when the clutch member 27 105 is out of engagement with the clutch member 17. This observation is necessarily true, because, clearly, the shaft 5 cannot be coupled at one time to the oppositely rotating pulleys 6 and 14. During the aforesaid 110 interval, some means must be provided for moving the slide 23, and consequently the clutch member 27, to the left, because if, for an instant, neither the pulley 6 nor the pulley 14 drives the shaft 5, the screw 41, 115 the nut 43, the shift bar 35 and the lever 36 will be of no effect, so far as moving the clutch member 27 into engagement with the clutch member 17 is concerned. It is at this time that the actuators 47 do their work.

120 Note Figure 9. The actuators 47 are thrust upwardly by the springs 50, and, coacting with the inclines at the right hand end of the cam tracks 51, carry the slide 23 and the clutch 27 to the left until the said part 27 cooperates with the clutch element 17 on the pulley 14. When the pulley 14 becomes a driving means, the direction of rotation of the screw 41 is reversed, and the direction of travel of the nut 43 and the shift bar 35 is re-

versed, the lever 37 moving the clutch member 31 to the right, and the actuators 47 operating at the left hand ends of the cam tracks 51 (Figure 9) in a way which will be understood clearly in view of what has been stated hereinbefore.

I claim:—

1. In a device of the class described, a tap shaft; a driven shaft disposed at an angle to the tap shaft; means for connecting the shafts operatively; means for raising and lowering the tap shaft responsive to a change in the direction of rotation of the tap shaft; rotatable members loose on the driven shaft; a screw on the driven shaft; a nut traversing the screw; clutch means on the driven shaft for connecting the rotatable members, one at a time, with the driven shaft; and mechanism operated by the nut for moving the clutch means in opposite directions toward the respective rotatable members—said mechanism comprising a shift bar supported for right line sliding movement; stops on the shift bar, for engagement by the nut; and movable elements operated by the shift bar and coacting with the clutch means to move the same in opposite directions.
2. In a device of the class described, a tap shaft; a driven shaft disposed at an angle to the tap shaft; means for connecting the shafts operatively; means for raising and lowering the tap shaft responsive to a change in the direction of rotation of the tap shaft; rotatable members loose on the driven shaft; a screw on the driven shaft; a nut traversing the screw; clutch means on the driven shaft for connecting the rotatable members, one at a time, with the driven shaft; and mechanism operated by the nut for moving the clutch means in opposite directions toward the respective rotatable members—said mechanism comprising a shift bar supported for right line sliding movement; stops on the bar, on opposite sides of the nut, and engageable thereby; levers cooperating with the clutch means and pivoted to the shift bar; and fulcra supporting the levers, intermediate their ends.
3. In a device of the class described, a tap shaft; a driven shaft disposed at an angle to the tap shaft; means for connect-

ing the shafts operatively; means for raising and lowering the tap shaft, responsive to a change in the direction of rotation of the tap shaft; rotatable members journaled on the tap shaft; clutch means movable longitudinally of the driven shaft and connecting the rotatable members one at a time with the driven shaft; means responsive to a change in the direction of rotation of the driven shaft for moving the clutch means toward the respective driven members; a cam track on the clutch means; and a spring-operated actuator on the means responsive to a change in the direction of rotation of the driven shaft, and coacting with the cam track, to move the clutch means into engagement with the respective rotatable members when the clutch means is in a neutral position.

4. In a device of the class described, a driven shaft; rotatable members loose on the driven shaft; clutches slideable on the shaft and cooperating, one at a time, with the rotatable members; a slide connecting the clutches; a cam track on the slide; a screw on the driven shaft; a nut traversing the screw; a spring-operated actuator on the nut and coacting with the cam track to operate the clutches when the same are in a neutral position; a tap shaft disposed at an angle to the driven shaft; means for connecting the shafts; means for imparting endwise movement to the tap shaft, in opposite directions, responsive to a change in the direction of rotation of the tap shaft; and mechanism actuated by the nut for moving the clutches, one at a time, toward the respective rotatable members—said mechanism comprising a shift bar mounted for right line sliding movement; stops on the shift bar, in the path of the nut; levers cooperating with the clutches and pivoted to the shift bar; and fulcra whereon the levers are supported intermediate their ends.

In testimony that I claim the foregoing as my own, I have hereto affixed my signature in the presence of two witnesses.

FRANK E. BESSLER.
